UNITED STATES PATENT OFFICE.

GEORGE CALDER, JR., OF LANCASTER, PENNSYLVANIA, ASSIGNOR TO MARY H. CALDER, OF SAME PLACE.

MATRIX-MAKING MACHINE.

SPECIFICATION forming part of Letters Patent No. 444,124, dated January 6, 1891.

Application filed January 13, 1890. Serial No. 336,736. (No model.)

To all whom it may concern:

Be it known that I, GEORGE CALDER, Jr., a citizen of the United States, residing at Lancaster, in the county of Lancaster and State 5 of Pennsylvania, have invented certain new and useful Improvements in Matrix-Making Machines; and I do hereby declare the following to be a full, clear, and exact description of the invention, such as will enable others 10 skilled in the art to which it appertains to make and use the same.

The object of the invention is to provide means for impressing matrices with ease and rapidity; and it consists in the matters here- 15 inafter described and pointed out.

In the accompanying drawings, Figure 1 is an end elevation, partly in section. Fig. 2 is a plan in part of the key-board or alphabet-table. Fig. 3 is a top plan view, partly in 20 section, of the matrix bed or cylinder and mechanism for moving it. Fig. 4 is a side elevation of the same partly in section. Fig. 5 is a vertical section of devices for moving a type-carrier. Fig. 6 is a similar view of a 25 type-forcing hammer. Fig. 7 is an end view of the type-carrier, the hammer-head being shown in side view as it appears when about to impress the type upon the matrix; and Fig. 30 8 is a view of a detail of the type-moving mechanism. Fig. 9 is a detail showing connection of pivoted finger and cylinder.

The matrix is supported on part 1 of the two-part cylinder shown. This cylinder is supported to turn freely on axis or shaft 2, 35 and the part 1 is made longer than part 3 and arranged to be moved upon it longitudinally, a device 4 similar to a spline being provided to prevent their independent rotation. The longitudinal movement of the matrix-bed is 40 effected through circular rack 5 (ratchet-wheel) and pinions 6, idle-wheel 7, pinion 8, and miter-gears 9 and 10. The latter is affixed to a sleeve turning loosely on shaft 2, and said sleeve or a cylinder fixed thereon 45 and extended within the matrix-cylinder is provided with a spiral thread.

11 is a pivoted pin or finger pivotally connected with the movable part 1 of the two-part cylinder and provided on one side with 50 a stop 12' in such manner that the pin is nor-

mally held in the screw-thread on the shaft when it revolves from right to left, so that said matrix-cylinder will be moved lengthwise on part 3 by the revolution of the threaded cylinder.

To provide for the free return of cylinder 1, the pin 11, which is pivoted to the cylinder at 11', is disengaged from the screw-thread by moving bar 14' by means hereinafter described, which movement of said bar causes 60 the pin to be inclined, as indicated in dotted lines in Fig. 9, so that it will be trailed across the screw-threads upon the return of the cylinder, to which it is pivotally connected. It should be noted that in Fig. 9 the side shown 65 is opposite to that seen in Fig. 4.

The rack 5 is operated to turn the grooved cylinder and move the matrix-cylinder lengthwise by means of pawls 25, each pivoted to a sliding plate 26, which is forced forward 70 against springs 27 by the cam or projection 28 on any one of the series of operating-rods or key-levers 29, the extent of the movement being determined by the cam. Each rod is appropriate to a type or space of a particular 75 thickness, and the cam is of suitable form and size to move plate 26, rack 5, and mediate the matrix a distance corresponding to said type or space. The perpendicular face of the cam is adapted to prevent the return of plate 80 26 by the springs 27, while the rod is descending lower to effect objects to be hereinafter described.

The rack 5 and the sliding plates that carry the driving-pawls are supported in substantially the same horizontal plane by a table attached to the frame of the machine, said table being suitably slotted to permit the passage of the operating-rod. Key-rods representing letters of the same space are so grouped 85 as to operate upon the same sliding plates and have cams of substantially the same form and size. The grooved cylinder being turned by the successive action of the rods 29, the pivoted finger 11 will traverse the whole length 90 of its groove and pass out of the same and be thrown out of operative position by a tripping device 12, which at the proper time is struck by the sliding bar 14', which is thereby 95 moved endwise, the pivoted pin loosely con- 100

nected thereto being thereby tilted on its axis and thrown out of its groove, so that the matrix-cylinder can be returned without the revolution of the grooved cylinder. Upon its return the bar 14' strikes an annular projection or bumper 13, and the pin 11 is tilted back on its pivot and is returned to its operative position at the end of the grooved cylinder and near the enlarged mouth of the groove, 10 a spring 14 being provided to move the matrix-cylinder and pin a short distance to enter said mouth. The spring 14 is put under tension by the means which returns the matrix-cylinder, which consists of devices for introducing compressed air or other fluid into part 3 of the two-part cylinder.

15 is a reservoir for compressed air, and 16 is a pipe communicating with it and with said cylinder 3 when cock 17 is turned by depressing the rod 18. A spring returns said rod and opens the escape-port of the waste-cock 17. Shaft 2 is made hollow for at least a part of its length, so that the cylinder 3 can receive the compressed air through it.

20 The same rod which turns the cock for the operation just described also rotates the matrix-cylinder. A ratchet-wheel 19, fixed on a shaft 20, is turned by the pawl 21 upon the descent of rod 18. The turning of shaft 20 and pinion 22, which engages gear-wheel 23, affixed to cylinder 3, turns the latter. This operation occurs when a complete line has been impressed on the matrix and it is necessary to move the latter to a new position 25 for a new line.

To provide for lines of different lengths, the ratio of gears 6 and 7 may be changed and a grooved cylinder of a length to correspond provided. To provide for a change in the 40 distance between lines, an adjustable stop 24 is provided, which limits the descent of the operating-rod.

45 Devices for moving type into proper position and impressing them upon the matrix will next be described.

In Fig. 7 (see also Figs. 5 and 6) is shown a type-carrier 31, affixed to a piston-rod 32. This carrier has four arms or branches, each adapted to support a type on its end. The 50 hammer 40 has in its face a hollow or slot of sufficient size to receive a type-supporting arm and permit the hammer-face at the sides of the slot to strike upon the sides of the transverse type-supporting arms, the type itself being untouched by said hammer. The particular form of the hollow opening or slot is not material, it being important, however, that the type-face be not struck by the hammer. Each of a series of type-carriers 31, affixed to 55 a piston-rod 32, moving in a cylinder 33, is pushed under the hammer 40 immediately above the proper point on the matrix by compressed air or similar fluid. Pipes 34 and 35 communicating with the cylinders, one on each side of the piston, also communicate by means of one of a series of pipes 37 with any convenient holder or source of compressed

air. Preferably a belt pipe or holder 38 is arranged a little below the top of the machine and connected with each of the series. 70 This annular holder can be supplied from any convenient source, as from reservoir 15 through pipe 39. Arms 41 and 42, fixed to suitable cocks in the pipes 34 and 35, respectively, are provided with devices or hands 75 43, which encompass a pin 44 on rod 29. These hands or rings are made sufficiently large and so arranged that the rod may move a short space without coming in contact with them. This part of the descent of the rod 80 moves the matrix material the distance of a letter, as above described, and the continued descent of the rod reverses the position of the cocks illustrated in Fig. 5, so that cock 45 is closed to the external air and permits 85 compressed air to pass to the rear of piston 47 and cock 46 is opened to the external air. The type-carrier is thus pushed to its operative position. In the meantime the rod 29 has reached lever 48 and raised the pivoted levers and weight 54, loosely connected thereto, with the effect of moving crank-arm 50, fixed to cocks similar to 45 and 46 and similarly arranged, whereby compressed air is admitted to pipe 51 and above piston 52 to 90 operate the hammer 40, which descends upon the type-carrier, (see Fig. 7,) pipe 53 receiving waste air, which is passed out of cock 50'. It should be understood that cocks 50' and 50'', located in pipes 53 and 51, respectively, 95 are two way-cocks such as illustrated in Fig. 5, and that each is alternately put in open communication with cylinder 57 and with the open air, whereby air under pressure is admitted to said cylinder on one side of the piston and exhausted into the open air from the other, the construction and operation being substantially like that shown and described in connection with cocks 45 and 46. The rods 32 are elastic, and each carrying a type 100 is at the desired time moved out of its cylinder 33 by the means above stated to bring the type under the hammer, whereupon the cock in pipe 51 is opened to permit compressed air to enter cylinder 57 above the piston and 105 operate the hammer, the space in the cylinder below the piston being in free communication with the open air through the cock in pipe 53. Under the stroke of the hammer the rod 32, which is elastic, bends to permit 110 the type to descend upon the matrix, the elasticity of the rod being sufficient to throw it up when the hammer rises. A weight 54 reverses the cocks 50' and 50'' as soon as the finger of the operator is removed from rod 29, 115 and spring 55, put under tension by the previous descent of the rod, is allowed to expand and lift it. This reversal of the cocks admits compressed air below piston 52 and raises the hammer, air being wasted at cock 120 50''. Above hammer-piston 52 its rod is extended and provided with a second piston 56, working in cylinder 57', which is an extension of cylinder 57, but does not communi-

cate therewith. The resistance of air in this extension can be regulated by means of the cocks 58, and by this means the force of the hammer may be regulated. (See Fig. 6.) The 5 type-carrier is withdrawn simultaneously with the ascent of the hammer by the effect of spring 55, which carries pin 44 into engagement with rings 43, and restores the valves to the position shown in Fig. 5, which represents the work as accomplished.

59 are fingers designed to enlarge the reach of devices 43 and insure their engagement with pin 44.

The type-carrier 31 has four faces, to each 15 of which is secured a type or mark, those of the same size or which occupy the same space on the matrix being grouped on the same carriers. These are each turned to bring any desired face or type into position to be impressed 20 on the matrix by a grooved cylinder 60, located in the cylinder or race 33, which cylinder 60 is rotated by means of a pin 61 moving in a slot 62 under the action of a sliding plate 63, which is pushed in by means of the bar or extension 62'. (See Figs. 5 and 6.)

At 64 is indicated the upper end of a spring-wire, which enters each of the notches in succession if the bar is pushed inwardly a sufficient distance to cause an entire revolution 30 of cylinder 60 by means of pin 61. A spring for returning the plate is indicated at 65. Rod 32 is angular and passes through an angular opening at the axis of the cylinder 60, and is turned with it, as are also the type-carrier and piston 47.

It will be understood that the various types, marks, and characters supported upon type-carriers, together with the carrier-moving devices, are arranged and grouped in any convenient manner and number.

As arranged in Fig. 5, the operating or key board is intended for twenty-six carriers or one hundred and four distinct type on each side. This number can be increased. The 45 number of type supported by each carrier can be varied and other changes of like character made by mechanical skill, and particularly the air-pipes, such as 34 and 35, can be considerably extended, and in any desired 50 direction, without departure from the invention, and it will be convenient by this means to enable the operating-rods corresponding to those letters and characters which are ordinarily most used, or any others, to be located 55 at the front of the key-board.

It will be understood that one or more of the rods 29 will have no connection with the hammer-valve mechanism and will be adapted to move the matrix without making an impression to make proper spaces between the words or provide for other blanks in a line.

In my application, Serial No. 335,100, filed December 27, 1889, is described and claimed a combination of cylinders and pistons, type-carriers, and conduits provided with controlling-cocks for operating the piston-carrier by means of a compressed fluid, also the combi-

nation therewith of a piston-hammer, and also of a reciprocating key-rod. In the present case claims to combinations having general 70 resemblance to the above are limited to a revoluble type-carrier and to the particular means set forth for operating the levers attached to the cocks in the conduits for compressed fluid.

In application, Serial No. 338,744, filed January 31, 1890, I have described and claimed particular mechanism, including a type-carrier for several series of type, in combination with a rack and gear, the latter being so connected to the rod of the type-carrier that they revolve together, while free endwise motion of the rod and carrier is permitted, and also in combination therewith a cylinder, piston, and air-inlet for moving the carrier, and such 85 matters are not of the present invention.

Having thus described my invention, what I desire to claim and secure by Letters Patent is—

1. In a matrix-impressing machine, the two-part cylinder, one part being adapted to receive a matrix material and be moved upon the other longitudinally by the type-operating mechanism, and a conduit communicating with a reservoir or other source of compressed air and with the interior of said cylinder, substantially as set forth.

2. In a matrix-impressing machine, the two-part cylinder, one part being adapted to receive a matrix material and be moved upon the other longitudinally by the type-operating mechanism, a conduit communicating with a reservoir or other source of compressed air and with the interior of said cylinder, an operating-rod provided with a projection corresponding to the thickness of a type, devices for moving type into proper position adjacent to the matrix material, and intermediate mechanism, whereby the rod moves the matrix-supporting cylinder a distance equal to the thickness of a type, substantially as set forth.

3. In a matrix-impressing machine, the type-carrier and its rod provided with a piston, the piston-cylinder, conduits for compressed air communicating with the cylinder each side of the piston, the operating-rod provided with a pin, and cocks in the air-pipes, provided with arms having rings arranged to surround and engage said pin when the rod is moved and serving to change the position of the valves to alternately admit air on one side of the piston and simultaneously waste the air from the other side, substantially as set forth.

4. In a matrix-impressing machine, a type-carrier provided with several faces, each adapted to receive a type, a rod and piston connected thereto, a piston-cylinder, a grooved cylinder surrounding the rod and having an angular connection therewith to permit endwise movement of the rod through said grooved cylinder while compelling them to rotate together, and a pin engaging the groove in the

cylinder and movable in a slot in an extension of the piston-cylinder, whereby the type-carrier can be turned, substantially as set forth.

5. In a matrix-impressing machine, a cylinder and piston, a revoluble type-carrier, the carrier being connected to the piston in said cylinder, and devices for admitting air to suitably move the piston and carrier, substantially as set forth.

10. 6. In a matrix-impressing machine, a hammer provided with a slot or opening in its face, and a type-carrier having type on opposite portions thereof, said opening in the hammer being of a size to embrace a type on one side and permit the hammer-face to strike the carrier to print or impress the opposite type, substantially as set forth.

15. 7. In a matrix-machine, a cylinder, a piston having its rod extended through one end of the cylinder and provided with a hammer, said rod being also extended through the opposite end of the cylinder, which is made close and provided with a piston, and a second closed cylinder in which the last-named piston plays, said second cylinder being provided with cocks to regulate the escape of air from the same, whereby all egress of air is regulated and whereby the force of the hammer-stroke 20 may be controlled and adjusted, in combination with a type-carrier, substantially as set forth.

25. 8. In a matrix-impressing machine, a piston-hammer, the cylinder in which the piston moves, conduits communicating therewith, one on each side of the piston, and with a reservoir or other source of compressed air, cocks located in the conduits, provided with arms connected by bars pivoted thereto and 30 to each other, a lever adapted to move the

35. arms and cocks to permit compressed air to pour through one and waste from the other alternately, means for reversing the cocks when the rod is released from the lever, and an operating-rod in the path of which the lever is arranged, substantially as set forth. 45

9. In a matrix-impressing machine, the matrix-cylinder provided with a gear, the pinion, and its axis, having thereon a ratchet, in combination with the operating-rod having a pawl 50 pivoted thereto, and devices for returning the matrix-cylinder longitudinally to its initial position, said devices being adapted to be made simultaneously operative by the rod which moves the ratchet to turn the cylinder 55 circumferentially, substantially as set forth.

10. In a matrix-impressing machine, the matrix-cylinder provided with a gear, the pinion, and its axis, having thereon a ratchet, in combination with the operating-rod having a 60 pawl pivoted thereto, and a stop arranged in the path of a projection on the rod and made adjustable to permit the extent of the movement of the pawl and the rotation of the cylinder at each operation to be varied, substantially as set forth. 65

11. In a matrix-impressing machine, a cylinder, a piston connected to a type-carrier, a pipe or reservoir for compressed air, located immediately under the table constituting the 70 top of the machine, and pipes or conduits communicating with the reservoir and with the cylinder on each side of the piston, substantially as set forth.

In testimony whereof I affix my signature in 75 presence of two witnesses.

GEORGE CALDER, JR.
